UNITED STATES PATENT OFFICE

2,463,381

PORTABLE LIFT

Marvin L. Hicks, Vallejo, Calif., assignor of one-half to Rufus N. Ward, Greenville, S. C.

Application August 7, 1944, Serial No. 548,425

2 Claims. (Cl. 254—2)

1

The invention relates to a novel portable lift, and more particularly has reference to a portable lift whereby heavy objects such as pianos, electric refrigerators, ranges, furniture, boxes and the like may be moved along substantially smooth surfaces with ease and safety and without scarring, rubbing, or otherwise damaging either the object being moved or the floors.

Another object of my invention is to provide a portable lift of the character described wherein the object carried thereby may be readily "spotted" in the exact location desired.

Another object of my invention is to provide a portable lift of the type above described which may be readily operated by a single individual.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which:

Figure 1 is a view in side elevation showing the portable lift in position relative to an object to be moved, the lift disposed at the right hand corner of the object being broken away.

Figure 2 is a sectional view taken along the line 2—2 of Figure 1, looking in the direction of the arrows.

Figure 3 is a perspective view of the detachable lift extension.

Figure 4 is a perspective view of the adjustable buffer roller.

Figure 5 is a view taken along the line 5—5 of Figure 4, looking in the direction of the arrows, but being on a slightly enlarged scale.

As shown in Figure 2, the portable lift includes a base or chassis 1 which is provided adjacent each end thereof with a bifurcated member 17, each bifurcated member being supported by a shaft (not shown), which extends through an aperture in the base and projects into a housing 15 anchored to the upper face of the base, and suitable ball bearings are disposed within the housing so that the bifurcated member may have swivelling movement. A wheel 18, preferably provided with a pneumatic tire, is journaled in the arms of each bifurcated member 17 so that the chassis 1 may be readily moved along the floor or other surface.

A pair of boxes or supports 16 are also secured to the chassis 1, and a vertically disposed shaft 3

2

is conveniently attached within each box 16. A frame 4 having a pair of spaced horizontal members connected at their free end by spaced vertical members is provided along each vertical member with a pair of sleeves 5 which are adapted to encircle the shafts 3 in order that the frame 4 may have vertical movement relative to the shafts 3. A plate or equalization bar 13 is supported by the frame 4 intermediate the horizontal members by means of braces 14. The raising of the frame 4 is controlled by a hydraulic unit, such as a jack 2, the piston rod 12 of which engages the equalization bar, as clearly illustrated in Figure 2. A vertical rod 11 extends from the bar 13 to the upper horizontal member of the frame 4. To elevate the piston rod 12, a foot pedal 24 is associated therewith and to lower the rod the foot treadle 26 is employed, and since this assembly is well known in the art, no further description is believed necessary.

In order to employ the unit to move an object such as shown in Figure 1, I provide a lift assembly which is adapted to be detachably connected with the frame 4, and as shown in Figure 25, this unit includes spaced vertical supports 19 which are connected by means of horizontal elements 20 attached at their free ends to the supports 19 by welding or the like. An extension 21 is carried by the lower end of the supports 19 and may be strengthened or reinforced by braces 25 secured to the supports and the extension 21. In order to connect the lift to the frame, it will be observed that each support 19 is provided with a pair of spaced substantially horizontally extending arms 22, and the free end of each arm is recessed to fit over a stud 8 provided on each of the sleeves 5. Hence, it can be seen that the lift may be readily attached to or removed from the movable frame 4.

40 A buffer roller 9 of any desirable type is supported by spaced arms 30 of a reinforcing frame 31 and the opposite or free end of the arms 30 supports a handle 23. Intermediate the ends of each arm 1 I provide a sleeve 32 which is adapted to encircle each shaft 3 adjacent the upper end thereof, and the frame 31 may be locked at any desired position on the shafts 3 by manipulating a set screw 33 associated with each of the sleeves 32.

45 In operation, the lift is attached to the frame 4 by means of the arms 22 and the lift is moved forward with respect to the object until the plate 21 is located therebeneath, it being understood, of course, that the second lift is disposed at the opposite side of the object in the same manner.

To stabilize the lifts, it will be noted that each sleeve 32 of the frame 31 is provided with a holder 7 and a similar holder 7' is attached to the base at each end thereof. A tie bar or rod 27 is then secured to each of the holders 7 by a nut 28, thereby tying the respective lifts together. If perchance the roller 9 does not engage the surface of the object, the nuts should be further adjusted in order that the roller will contact the object, thereby holding the object secure to the lifts. The foot treadle is then actuated, thereby elevating the frame 4 and, as a consequence, the lift until the object is moved to the desired height above the surface such as shown in the dash line in Figure 1. The lifts may be readily moved in any direction by virtue of the castering movement of the wheels 18, and the units may be guided by the pressure on the handle 23 of either lift.

I claim:

1. A portable lifting device comprising a wheeled base, a vertically movable jack mounted on said base, a pair of spaced uprights secured to said base and extending upwardly therefrom, a frame slidably mounted on said uprights operatively associated with said jack and movable vertically with said jack, said frame having trunnions extending beyond said frame, a lifting

platform detachably suspended on said trunnions, a vertically adjustable buffer roller adjustably mounted between said uprights at one end thereof in alignment with said lifting platform, said base and said roller each having a pair of brackets extending beyond said trunnions.

2. The combination set forth in claim 1 including a tie bar, said tie bar adapted to be adjustably secured in said brackets when a pair of said lifting devices are utilized with the load therebetween for the purpose of securing the load and lifts together.

MARVIN L. HICKS.
